1

Botanical designation: ***Chrysanthemum×morifolium*** Ramat.

Cultivar denomination: 'Zanmucanyon'.

RELATED CULTIVARS

This new plant cultivar 'Zanmucanyon' is of the botanical classification *Chrysanthemum×morifolium* Ramat and is related to 'Zanmurover' (U.S. plant patent application No. 12/926,550). Both are seedlings from the same cross.

BACKGROUND OF THE INVENTION

The present invention relates to a new and distinct cultivar of *chrysanthemum* plant, botanically known as *Chrysanthemum×morifolium* Ramat., commercially known as a garden mum, and hereinafter referred to by the cultivar denomination 'Zanmucanyon'. 'Zanmucanyon' is a product of a breeding and selection program for outdoor pot mums (garden mums) which had the objective of creating new cultivars with a double type inflorescence, a natural season flower date around October 5 (week 41), blooming for a period of 4 weeks. 'Zanmucanyon' is a seedling resulting from a cross of the female parent id 9396 with the male parent id 9285. Plants of the new cultivar 'Zanmucanyon' differ from plants of the female parent in the following characteristics. (1) Natural season flowering date. And (2) Inflorescence size. (1) Plants of the seedling flower later in the season than those of the female parent. (2) Inflorescences of the seedling smaller than those of the female parent.

Plants of the new cultivar 'Zanmucanyon' differ from plants of the male parent in plant habit. Plants of the male parent grow more upright than those of the seedling.

The new and distinct cultivar was discovered and selected as a flowering plant by Wilhelmus Bernardus Blom on a cultivated field in Rijsenhout, The Netherlands in 2005. The first act of asexual production of 'Zanmucanyon' was accomplished when vegetative cuttings from the initial selection in 2005 were propagated further in a controlled environment in Rijsenhout, The Netherlands. The new cultivar has been found to retain its distinctive characteristics through successive propagations.

(57) ABSTRACT

A *chrysanthemum* plant named 'Zanmucanyon' characterized by its medium sized blooms with dark red ray florets and prolific branching; natural season flower date October 5 (week 41); blooming for a period of 4 weeks.

3 Drawing Sheets

2

BRIEF DESCRIPTION OF THE DRAWINGS

The present invention of a new and distinct variety of *chrysanthemum* is shown in the accompanying drawings, the color being as nearly true as possible with color photographs of this type.

FIG. 1 shows a plant of the cultivar in full bloom.

FIG. 2 shows the various stages of bloom of the new cultivar.

FIG. 3 shows the various stages of foliage of the new cultivar.

DESCRIPTION OF THE INVENTION

The observations and measurements were gathered from plants grown out door in Rijsenhout, The Netherlands under natural day length and temperature and planted in week 23 in 2009. The natural blooming date of this crop was October 5 (week 41). The average height of the plants was 26 cm. No growth retardants were used. No tests were done on disease or insect resistance or susceptibility. No tests were done on cold or drought tolerance. This new variety produces medium sized blooms with dark red ray florets blooming for a period of 4 weeks.

From the cultivars known to inventor the most similar existing cultivar in comparison to 'Zanmucanyon' is its sibling 'Zanmurover' (U.S. Plant Patent applied.). When 'Zanmurover' and 'Zanmucanyon' are being compared the following differences are noticed (1) Plant vigor. And (2) Leaf size. (1) Plants of 'Zanmucanyon' are less vigorous than those of 'Zanmurover'. (2) Leaves of 'Zanmucanyon' are larger than those of 'Zanmurover'.

The following is a description of the plant and characteristics that distinguish 'Zanmucanyon' as a new and distinct variety.

The color designations are taken from the plant itself. Accordingly, any discrepancies between the color designations and the colors depicted in the photographs are due to photographic tolerances. The color chart used in this description is: The Royal Horticultural Society Colour Chart, edition 2001.

TABLE 1

Botanical Description of <i>Chrysanthemum xmorifolium</i> Ramat. 'Zannucanyon'	
Bud	
Size	Small; cross-section 5 mm, height 5 mm
Shape	Round
Texture	Pubescent
Outside Color	Greyed-green 191A
Phyllaries	
Number	30, arranged in 3 rows
Shape	Elliptic
Apex	Acute
Base	Truncate
Margin	Entire
Color	Upper surface: Greyed-green 191B
Length and width	5 mm; 2 mm
Texture	Pubescent
Inflorescence	
Type	Double
Height	1.4 cm
Diameter	3.8 cm
Peduncle length	5 cm
Peduncle color	Green 138B
Peduncle diameter	1.8 mm
Peduncle texture	Pubescent
Number per branch	Approx 7 inflorescences
Duration of flowering	4 weeks
Seeds	Produced in small quantities, ovate, Greyed-brown 199A, length 1.5 mm, diameter 0.5 mm
Fragrance	Faint <i>chrysanthemum</i> odor
Color	
Center of inflorescence	Immature stage: Yellow-green N144D Mature stage: Yellow 13A
Color of upper surface of the ray-florets	Yellow 6C at base, upper part Red-purple 60A
Color of the lower surface of the ray-florets	Greyed-red 180D
Tonality from Distance	A garden <i>mum</i> with dark red flowers
Color of the ray-florets after aging of the plant	Greyed-purple 187C
Ray florets	
Texture	Upper and lower surface smooth
Number	200-210
Shape	Elliptic
Apex	Dentate
Base	Attenuate
Cross-section	Flat
Longitudinal axis of majority	Straight
Length of corolla tube	3-5 mm
Ray-floret margin	Entire
Ray-floret length	1.4-1.8 cm
Ray-floret width	3-5 mm
Ratio length/width	Medium
Disc florets	
Disc diameter	1-2 mm
Distribution of disc florets	Few, only visible in mature stage of inflorescence
Shape	Tubular
Color	Yellow-green 145C at base to Green Yellow 1D at top
Length	4 mm
Receptacle	
Color	Yellow-green 145D
Shape	Domed raised
Height	5 mm
Diameter	3 mm

4

TABLE 1-continued

Botanical Description of <i>Chrysanthemum xmorifolium</i> Ramat. 'Zannucanyon'	
5 Reproductive Organs	
Androecium	Present on only disc florets
Stamen length	3 mm
Stamen color	Yellow-green 144A
Anther color	Yellow 6D
10 Pollen	Present
Pollen color	Yellow 13A
Gynoecium	Present on both ray and disc florets
Style color	Yellow-green 154C
Style Length	3 mm
Stigma color	Yellow 7A
Stigma Width	1 mm
15 Ovary	Enclosed in calyx
Plant	
Form	Grown as a spray type pot <i>mum</i> , outdoor raised and mounded
20 Growth habit	Spherical shape
Growth rate	Medium
Height	26 cm
Width	45 cm
Stem Color	Greyed-brown 199A
Stem Strength	Not strong
Stem Brittleness	Brittle
25 Stem Anthocyanin Coloration	Not observed
Internode length	0.5-1 cm
Length of lateral branch	From top to bottom 13 cm
Lateral branch color	Green 137 C
Lateral branch, attachment	Brittle
Lateral branch diameter	2 mm
30 Branching (average number of lateral branches)	Prolific with 8 breaks after pinching
Natural season blooming date	October 5 (week 41)
Foliage	
Leaf color	Upper side: Yellow-green 147A Lower side: Green 139C
35 Color midvein	Upper side: Yellow-green 147D Lower side: Yellow-green 148D
Size	Small; length 4-5 cm, width 3-3.5 cm
Quantity (number per lateral branch)	Ca. 15
Shape	Elliptic
40 Texture upper side	Sparsely pubescent
Texture under side	Pubescent
Venation arrangement	Palmate
Shape of the margin	Serrated
Shape of Base of Sinus	Rounded
Between Lateral Lobes	
45 Margin of Sinus Between Lateral Lobes	Diverging
Shape of Base	Attenuate to truncate
Apex	Mucronulate
Petiole length	1 cm
Petiole diameter	2 mm
50 Petiole color	Yellow-green 147D

TABLE 2

55 Differences with the comparison variety (when grown side to side)		
	"Zannucanyon"	'Zannuover'
Growth rate	Medium	High
Leaf length	4-5 cm	2.5-4 cm
Leaf width	3-3.5 cm	1.5-2.5 cm

I claim:

1. A new and distinct *chrysanthemum* plant named 'Zannucanyon' as described and illustrated.
